UNITED STATES PATENT OFFICE.

JOSEPH W. SCHOENDELEN, OF OGDEN, UTAH, ASSIGNOR TO AMERICAN CAN COMPANY, OF NEW YORK, N. Y., A CORPORATION OF NEW JERSEY.

SHEET-GAUGING DEVICE FOR PRESSES.

Application filed November 19, 1923. Serial No. 675,459.

To all whom it may concern:

Be it known that I, JOSEPH W. SCHOENDELEN, a citizen of the United States, residing in Ogden, in the county of Weber and State 5 of Utah, have invented a new and useful Improvement in Sheet-Gauging Devices for Presses, of which the following is a specification.

This invention has to do with punch presses by which pieces of suitable form and size are cut from metal sheets for use in the making of can ends, or the like, and the particular improvement provided is for the purpose of properly gauging the sheets in their various operative positions as they 10 are passed through the press.

An important object of the invention is the provision of a device for this purpose which is automatically operable in synchronism with the feeding of the sheets and the 15 action of the punch.

A further object is the provision of a sheet gauging device which may be placed upon presses of standard form and construction, 20 and which involves relatively simple mechanism adapted to perform its intended function without likelihood of breakage, or the necessity for frequent repair and without 25 complicating the structure, or operation of the machine.

Numerous other objects and advantages 30 of the invention will be apparent as it is better understood from the following description, which, taken in connection with 35 the accompanying drawings, discloses a preferred embodiment thereof.

Referring to the drawings,

Figure 1 is a side elevation of a standard press upon which a device embodying 40 my invention is employed, being partially broken away to better illustrate some of the operating elements;

Fig. 2 is a front end elevation, taken substantially along the line 2-2 of Fig. 1;

Fig. 3 is a plan view of the bed of the press, being taken substantially along the broken line 3-3 in Fig. 1; and

Fig. 4 is a detail perspective view of the device of my invention, shown apart from 50 the other mechanism.

The general organization of the machine, which has been shown on the drawings for purposes of illustration, is well-known and need not be described in particular detail.

A frame 11 is supported from base members 55 12 and has mounted in the upper part thereof a crank shaft 13 which carries a driving pulley 14, a cross-head 15 and brake mechanism 16. An upper slide 17 is suspended from the cross-head 15 and carries 60 a punch 18 adapted to cooperate with a die member (not shown) mounted in a die block 19, which in turn is supported by a bolster plate 21 resting upon an extension bed plate 22 upon the frame 11. A feeding 65 table 23 is provided above the die block 19 and is supported at its front end by means of a bracket 24 secured to the bed plate 22, the rear end of said table being supported by means of a web 25 70 extending between the sides of the press frame.

Referring now in detail to the mechanism provided by my invention, it will be noted that a short shaft 26 is mounted in 75 bearings 27 and 28 secured to the side of the feeding table 23 and is adapted to be rotated by means of a spiral gear 29 meshing with a spiral gear 31 mounted on the end of a transverse shaft 32, which is 80 journaled in a bearing 33 and is driven from the crank shaft 13 by means of a sprocket chain 34 taking over sprockets 35 and 36 mounted respectively on the shafts 32 and 85 13.

A plurality of equally spaced fingers 37 are mounted upon the shaft 26 and project radially from different points about the circumference thereof in predetermined relationship for a purpose which will hereinafter appear.

A side guide 38 is provided upon the table 23 and a retaining bar 39 extends laterally therefrom and is adapted to prevent upward displacement of the sheets as 90 they are successively fed through the machine.

For the purpose of feeding said sheets, I employ a mechanism which will now be described. A short transverse shaft 41 is 100 journaled in a bearing 42 secured to the edge of the table 23 and carries on its inner end an eccentric 43, which is adapted to periodically engage and advance a sheet 44 during the rotation of said shaft, which is accomplished by means of a chain and sprocket connection with the shaft 32. This connection comprises a chain 45 taking over 105 46

a sprocket 46 on said shaft 41 and over a sprocket 47 mounted on the shaft 32 adjacent the sprocket 35.

It will be understood that upon each revolution of the shaft 41, the eccentric 43 engages the sheet 44 and advances it a predetermined distance, this being the distance between the cuts which have been indicated by the reference character 48. This action 10 is synchronized with the action of the punch 18 so that the sheet is advanced one step for each stroke of said punch, it being understood that the advance takes place while the punch is in its raised position.

15 When the sheet is in position for the first cut, its forward edge rests against the forward finger 37, which at this time extends vertically downward and forms a stop accurately locating said sheet in desired position. The shaft 26 rotates in such timed 20 relation that it makes a quarter turn at each stroke of the punch and each revolution of the shaft 41. Upon the next feeding action, therefore, the forward edge of the sheet is 25 brought into contact with the second finger 37, which has by this time assumed the downward position and the sheet is held for the second stroke of the punch. Further 30 rotation of the shaft 26 results in stopping the sheet at the proper positions for the remaining cuts to be made (there being in 35 the present instance four cuts in the length of the sheet) and when these are completed, the sheet is discharged from the machine, falling by gravity to any desired place of 40 deposit. Thus the sheets are properly gauged and brought to rest at the successive operative positions by wholly automatic mechanism and without the necessity of any manual handling.

It is thought that the invention and many of its attendant advantages will be understood from the foregoing description, and it will be apparent that various changes 45 may be made in the form, construction and arrangement of the parts without departing from the spirit and scope of the invention, or sacrificing all of its material advantages, the form hereinbefore described 50 being merely a preferred embodiment thereof.

I claim:

1. A sheet gauging device for presses and

the like, comprising a rotatable element arranged longitudinally of the path of travel 55 of the sheets and having a plurality of projections thereon adapted to be successively disposed in sheet obstruction position during the rotation of said element, a transverse shaft having a cam to bear intermittently 60 on the tops of the sheets, and means connecting said transverse shaft and rotatable element for operation in timed relation to each other.

2. A sheet gauging device for presses and 65 the like, comprising a shaft disposed longitudinally of the path of travel of the sheets and rotatable in timed relation with respect to the operation of the press, and means disposed along the length of said shaft and 70 successively projectable into the path of the sheets to gauge the same in the successive operative positions, a transverse shaft having a cam to bear intermittently on the 75 tops of the sheets, and means connecting said transverse shaft and longitudinal shaft for operation in timed relation to each other.

3. The combination with a press provided 80 with punching dies and means for advancing sheets of tin plate, or the like, into the sphere of action of said dies, of a rotatable element having a plurality of projections disposed along the length thereof and extending radially therefrom in different directions, said projections being successively 85 projectable into the path of a sheet to position it at the various operating positions, and a transverse shaft geared with said rotatable elements, a second transverse 90 shaft having a cam for intermittently propelling the sheets against said projections, and mechanism operating said transverse shafts and the punching dies.

4. In a press, the combination of reciprocating dies, means comprising a cam which bears intermittently on the tops of the sheets for feeding tin sheets, or the like, into the sphere of action of said dies, and means 95 automatically operable in timed relation with respect to the action of said feeding means to stop the sheet at a plurality of different points to permit the taking of successive cuts therefrom in exact predetermined order.

JOSEPH W. SCHOENDELEN,
